COIN CHUTE MECHANISM

David C. Rockola, Chicago, Ill., assignor to Rock-Ola Manufacturing Corporation, Chicago, Ill., a corporation of Illinois

Application November 21, 1947, Serial No. 787,382

4 Claims. (Cl. 194—1)

1

This invention relates in general to coin handling devices, and more particularly to novel coin chute mechanism.

A principal object of the invention is the provision in a coin chute, having an aperture for receiving coins, of a novel closure member mounted interiorly of the coin chute and normally resiliently held in position to close the coin-receiving aperture so as to weather-seal the coin chute.

More specifically, the closure member is provided with spring means for maintaining one surface thereof in engagement with that wall of the coin chute in which the coin-receiving aperture is located so as to underlie and close such aperture, the mounting of the closure member preferably comprising a pivot pin arranged in a slot in the member adjacent one end thereof, such slot being disposed normal to the wall engaging surface, with the spring means acting against that side of the member opposite its wall engaging surface in offset relationship to the pin and slot mounting of the closure member.

Another important object of the invention is to provide such a closure member in a coin chute which is movable out of aperture-closing position by a coin inserted through the coin-receiving aperture to further energize the spring means normally maintaining the member in aperture-closing position to cause such spring means to react against a coin so deposited in the chute to impart movement inducing energy thereto.

A further important object of the invention is the provision in a coin chute, having a wall with a coin-receiving the aperture therein, of means disposed within the chute for automatically imparting movement inducing energy in a direction along the wall containing the coin-receiving aperture to a coin inserted therethrough.

Another object of the inventions is to provide such coin-actuating means which automatically will impart different degrees of energy to differently sized coins directly proportional to the size of the coin deposited.

More specifically, the coin-actuating means comprises a member mounted within the coin chute adjacent the coin-receiving aperture for pivotal movement only by small size coins inserted through the aperture, together with spring means adapted to be tensioned or energized to a predetermined degree by such coin-actuated pivotal movement of the member, and wherein the member is so mounted as to receive additional translational displacement by larger coins

2

inserted through the coin-receiving aperture to further energize the spring means to a degree proportional to the size of the deposited coin, whereby movement inducing energy will be imparted to any deposited coin directly proportional to the size of the coin. Consequently, if the wall of the chute containing the coin-receiving aperture is disposed horizontally, for example, all deposited coins will be impelled along the chute a predetermined distance, regardless of their size.

Numerous other objects and advantages of the invention will be apparent as it is better understood from the following description, which, when taken in connection with the accompanying drawings, discloses a preferred embodiment thereof.

In the drawings:

Figure 1 is a front elevational view, with parts broken away, of a coin chute embodying the instant invention;

Fig. 2 is a bottom plan view of the mechanism shown in Fig. 1;

Fig. 3 is a view similar to Fig. 1 showing the coin chute disposed in a horizontal position, with the coin-receiving slot in the upper wall thereof;

Fig. 4 is a top plan view of the mechanism shown in Fig. 3;

Fig. 5 is a view similar to Fig. 1, showing a dime being inserted through the coin-receiving aperture; and

Figs. 6 and 7 are views similar to Fig. 5, showing a penny and a nickel, respectively, being inserted in the coin-receiving aperture.

Referring more particularly to the drawings, reference numeral 11 indicates in general a coin chute embodying the features of the invention and shown in Fig. 1 as mounted in a vertical position and in Fig. 3 as mounted in a horizontal position. The coin chute 11 comprises a casing herein illustrated as made up of a channel-shaped member 12 having side walls 13 and a top or end wall 14, each of which terminates in an inwardly turned flange 15 disposed in parallel relationship to the main body portion of the member 12, and a front wall member 16 suitably retained between the flanges 15 and spacer members 17 (Fig. 2). As herein illustrated, the member 12 is of unitary construction and the front wall member 16 is made of any suitable plastic or other transparent material. It will be understood, of course, that this casing construction

55 may be modified in any desired manner, and that

the particular materials employed form no part of the present invention.

One of the side walls 13 is provided adjacent the end wall 14 with a coin-receiving aperture or slot 18 of such dimensions as to permit passage therethrough and into the casing of the largest sized coin intended to be accommodated by the coin chute and the mechanism (not shown) with which it is adapted to be employed. A pivot pin 19 secured in any suitable manner to the channel-shaped member 12 and extending normal to the rear wall thereof, is disposed interiorly of the casing in spaced relationship to the apertured side wall 13 adjacent that end of the coin slot 18 nearest the end wall 14.

A closure and coin-actuating member 21 is mounted on the pivot pin 19 for pivotal and translational movement relative thereto by means of a slot 22 engaging the pivot pin and arranged transversely of the member adjacent the upper end thereof. As illustrated herein, this closure member 21 is of sufficient length and width as to underlie and completely close the coin-receiving aperture 18 when the outer side surface thereof engages the inner surface of the apertured side wall 13, and the slot 22 is shown as formed by the inward and downward or reverse bending of a finger or extension 23 of such outer surface portion of the closure member which is formed integrally therewith. This reversely bent finger or extension 23 terminates at a point below or offset from the pivot pin 19 embraced thereby in an angularly disposed tail piece 24 for a purpose to be later more fully described.

Mounted in parallel relationship to the pivot pin 19, is a spring-supporting pin 25 which, if desired, may comprise a screw extending through the front wall member 16 and having threaded engagement at its rear end with a suitable tapped bushing secured to the rear wall portion of the channel-shaped member 12 so as to additionally function as a means for securing the front wall 16 of the casing in place. A coil spring, indicated generally by reference numeral 26, is mounted on this pin 25 with one of its ends 27 being reversely bent, as best seen in Fig. 2, and engaging against the end wall 14 of the casing, and its other end 28 terminating in a transversely disposed portion engaging the inner surface of the finger or extension 23 of the closure member 21. This end 28 of the spring 26 is so disposed with relation to the closure member 21 that it normally contacts the tail piece 24 of the finger 23, as illustrated in Figs. 1 and 3, to resiliently maintain the outer surface of the closure member 21 in firm contact with the inner surface of the apertured side wall 13 of the casing. The closure member 21 thus functions to weather-seal the coin-receiving aperture 18, the tail piece 24 functioning as a cam surface for cooperation with the end portion 28 of the spring 26 to insure complete surface engagement of the closure member with the apertured side wall 13 of the coin chute.

As will readily be appreciated, the pivot pin embracing slot 22 may be formed in the closure member 21 in any other desired manner, as by machining, and the cam-like tail piece 24 also may be formed as an integral extension of the inner surface of the member 21. The important feature of the mechanism so far described resides in the pin and slot mounting of the member 21 interiorly of the coin chute, so that the spring 26, or any other suitable resilient means, may engage the member 21 at a point offset from the

supporting pivot pin 19 so as to insure complete surface engagement between the closure member and the apertured wall of the coin chute. With this arrangement, any coin of suitable size 5 may be inserted through the slot 18 and pressed inwardly against the closure member 21 to displace the latter against the action of the spring 26, in the manner illustrated in Figs. 5 to 7, to permit deposit of the coin in the coin chute 11. 10 Thereafter, the spring 26 will function to return the closure member 21 to its normal position of Figs. 1 and 3.

In some types of coin controlled mechanism, the deposited coins function to release or actuate 15 control or operation-initiating mechanism, and the weight of the smaller sized coins alone may be insufficient to insure such operation, even when the coin chute 11 is mounted in a vertical position as illustrated in Fig. 1. The instant 20 mechanism obviates such difficulties by automatically imparting movement inducing energy to the deposited coins. In other types of coin controlled mechanism with which the instant 25 coin chute 11 is adapted to be employed, this same coin-actuating function may be used to move the deposited coins through the coin chute in an other than downward direction, or to insure movement of deposited coins of different sizes in a substantially horizontal direction to a terminal 30 delivery point horizontally spaced from the coin-receiving aperture 18. The member 21 is adapted to impart energy from the spring 26 to the deposited coins directly proportional to the different 35 sizes of such coins, in a manner to be fully described hereinafter, regardless of the difference in sizes of such deposited coins. The latter type of installation of the coin chute 11 is illustrated in Fig. 3.

The lower end of the coin-receiving aperture 40 18, or that remote from the pivot pin 19, is disposed in predetermined spaced relationship relative to this pivot pin so as to accomplish the desired result of automatically imparting movement inducing energy in different degrees to differently 45 sized coins directly proportional to the different sizes of the coins. For purposes of illustration, the instant coin slot 18 has been dimensioned to receive pennies, dimes and nickels. The width of the elongated closure member 21, the length of the slot 22 therein, and the position of the pivot pin 19 and the end of the coin-receiving 50 aperture 18 remote therefrom are so disposed that insertion of a nickel through the aperture 18 will impart maximum movement to the closure member 21 from its normally closed position of Fig. 1 to the position shown in Fig. 7. On the other hand, with this same arrangement of the several parts, insertion of a dime into the coin chute against the action of the spring 26 will 55 move the closure member 21 only as far as the position illustrated in Fig. 5. In other words, the spring 26 functions to resiliently maintain the inner end of the slot 22 in engagement with the pivot pin 19, and the several parts are so arranged that insertion of a dime into the coin chute through the aperture 18 will cause only 60 pivotal movement of the closure member 21 about the pin 19 to the position shown in Fig. 5, wherein a dime is designated by reference character D, the spring 26 functioning to maintain the edge of the inserted coin in engagement with that end of the coin-receiving aperture 18 remote from the pivot pin 19. Such pivotal movement of the closure member 21 energizes the spring 26 to a pre-determined degree, the spring being tensioned by 65 70 75

the resulting upward movement of its end 28 from the position of Fig. 1 to that of Fig. 5, and its other end 27 being maintained stationary against the end wall 14 of the casing. Consequently, upon completion of the insertion of a dime into the coin chute, this predetermined amount of energy thus stored in the spring 26 will be released to return the closure member 21 to its normal position of Fig. 1, and in so doing, the member 21 will impart movement inducing energy in the like 10 amount to the deposited dime.

With this same arrangement, insertion of a penny through the coin-receiving aperture 18 will first swing the closure member 21 inwardly against the action of the spring 26, in the same 15 manner as the insertion of a dime, and also, because of the larger size of the penny, will impart a small amount of translational movement to the member 21, as permitted by the slot 22, to move the member 21 to its position of Fig. 6, wherein 20 a penny is designated by reference character P. This incremental translational displacement of the member 21 will tension or energize the spring 26 to a further degree comprising an amount, additional to that resulting from the insertion of a dime, which is proportional to the difference between the sizes of a dime and a penny. Consequently, complete insertion of a penny into the coin chute 11 will result in movement inducing 25 energy being imparted to the penny by the spring 26 and coin-actuating member 21 which is greater than that imparted to a dime inserted in the coin chute, with the difference between the amounts of energy applied to a dime and a penny being directly proportional to the difference in sizes of 30 these two coins.

As illustrated in Fig. 7, insertion of a nickel N through the coin-receiving aperture 18 will first swing the closure member 21 about the pivot pin 19 in the same manner as results from insertion of a dime, and then will impart translational movement to the member 21 substantially to the extent limited by the slot 22. This translational movement of member 21 by the inserted nickel 35 is in greater degree than that imparted thereto by a penny and in direct proportion to the difference in sizes between a nickel and a penny. Consequently, it will be seen that a greater actuating force will be imparted to a larger coin inserted in the coin-receiving aperture 18 than to a smaller coin, and the several parts herein described are so dimensioned that the difference between the amounts of movement inducing energy thus imparted to the differently sized coins are directly 40 proportional to the difference between the diameters of the different coins.

If the coin chute 11 is mounted in a horizontal position, or any position other than a vertical position, as illustrated in Fig. 3, the net result of the deposit of differently sized coins therein through the coin-receiving aperture 18 will be to move the deposited coins along the coin chute in the direction of the apertured side wall 13 to a predetermined point or for a definite distance, regardless of the differences in diameter of the coins. When the coin chute 11 is mounted in a vertical position as shown in Fig. 1, coins inserted through the slot 18 will, of course, drop through the casing of the coin chute in response to gravity, but since the spring 26 retains the closure and coin-actuating member 21 in contact with any deposited coin throughout the movement of such coin through the aperture 18, the energy-imparting function of the member 21 will be performed in the same manner as though the coin chute 11 were disposed

in an other than vertical position, and the deposited coins will have movement inducing energy imparted thereto in a downward direction in varying degrees proportional to their different diameters. This is of material importance in some types of coin controlled mechanism, since it insures coin actuated control mechanism being operated by the lighter weight or smaller coins as well as by the larger ones. The instant mechanism also has the distinct advantage of being adaptable to mounting in a horizontal position, either as shown in Fig. 3 or in the reverse thereof with the apertured wall 13 forming the bottom wall of the casing, so that any coin inserted through the aperture 18 automatically will be impelled through the coin chute in the direction of the apertured wall. At the same time, the member 21 functions to perfectly weather-seal the coin-receiving aperture 18, so that the use of the instant coin chute in conjunction with outdoor installations, such as parking meters for example, will completely prevent water leakage into the operating portion of the mechanism through the coin-receiving aperture. At the same time, if sleet or ice should form over the coin-receiving aperture under such conditions, there is nothing to prevent anyone from inserting a coin into the coin chute merely by the application of pressure against the coin in sufficient degree to break through any film of ice so formed. It will be understood, of course, that resilient means different from the spring 26 herein illustrated may be employed to retain the closure member 21 in normal closing position, and it is not intended to limit the present invention to any particular shape, configuration or size of the coin chute.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A coin chute, comprising a casing having a coin-receiving aperture in one wall thereof, a pivot pin mounted interiorly of said casing adjacent one end of said aperture, a member having a slot engaging said pin, said slot normally being disposed substantially normal to said apertured wall, and a spring mounted interiorly of said casing and engaging said member to normally maintain the outer surface thereof in closing relationship to said aperture, said pivot pin normally engaging the inner end of said slot, the other end of said aperture remote from said pivot pin being disposed at a predetermined distance therefrom equal to the maximum diameter of a desired small size coin plus the distance from said outer surface of said member to the inner end of said slot less the diameter of said pin, so that small size coins not larger than said maximum diameter inserted through said aperture will cause only pivotal movement of said member about said pin, and larger size coins of greater than said maximum diameter inserted through said aperture will also cause translational displacement of said member relative to said pin as permitted by the length of said slot.

2. A coin chute, comprising a casing having a coin-receiving aperture in one wall thereof, a pivot pin mounted interiorly of said casing adjacent one end of said aperture, a member hav-

ing a slot engaging said pin, said slot normally being disposed substantially normal to said apertured wall, and a spring mounted interiorly of said casing and engaging said member to normally maintain the same in closing relationship to said aperture, said pivot pin normally engaging the inner end of said slot, the other end of said aperture remote from said pivot pin being disposed at a predetermined distance therefrom so that small size coins inserted through said aperture will cause only pivotal movement of said member about said pin and larger size coins inserted through said aperture also will cause translational displacement of said member relative to said pin as permitted by said slot, the straight line distance from said pivot pin to the end of said aperture remote therefrom being substantially equal to the diameter of the largest coin insertable through said aperture plus the distance from the outer end of said slot to the outer surface of said member, and said slot being substantially equal in length to the diameter of said pin plus the difference between the diameters of the largest and the smallest coins insertable through said aperture.

3. A coin chute, comprising a casing having a coin-receiving aperture in one wall thereof, a pivot pin mounted interiorly of said casing adjacent one end of said aperture, a member having a slot engaging said pin, said slot normally being disposed substantially normal to said apertured wall, and a spring mounted interiorly of said casing and engaging said member to normally maintain the outer surface thereof in closing relationship to said aperture, said pivot pin normally engaging the inner end of said slot, the other end of said aperture remote from said pivot pin being disposed at a predetermined distance therefrom equal to the maximum diameter of a desired small size coin plus the distance from said outer surface of said member to the inner end of said slot less the diameter of said pin, so that small size coins not larger than said maximum diameter inserted through said aperture will cause only pivotal movement of said member about said pin, and larger size coins of greater than said maximum diameter inserted through said aperture also will cause translational displacement of said member relative to said pin as permitted by the length of said slot, said spring engaging said member at a point offset from said pin, whereby pivotal movement of said member resulting from insertion of a smaller coin through said aperture will tension said spring a predetermined amount and the additional translational movement of said member resulting from inser-

tion of a larger coin through said aperture will tension said spring an additional predetermined amount proportional to the difference between the diameters of said smaller and larger coins, said spring thereby being adapted to impart different amounts of energy to said member corresponding to the diameters of the different coins inserted through said aperture to cause said member in turn to impart such energy to said coins.

4. A coin chute, comprising a casing having a coin-receiving aperture in one wall thereof, a pivot pin mounted within said casing adjacent one end of said aperture, an aperture-closing and coin-actuating member mounted interiorly of said casing and having a slot engaging said pin, a shaft mounted interiorly of said casing in parallel relationship to said pin, and a spring mounted on said shaft and engaging said casing at one end, the other end of said spring engaging said member in offset relationship to said pin to normally maintain the outer surface of said member in aperture-closing engagement with said wall, said pivot pin normally engaging the inner end of said slot, the other end of said aperture remote from said pivot pin being disposed at a predetermined distance therefrom equal to the maximum diameter of a selected small size coin plus the distance from said outer surface of said member to the inner end of said slot less the diameter of said pin, whereby insertion of a said small size coin through said aperture will pivotally move said member to an aperture-clearing position to tension said spring a predetermined amount to enable said spring to cause said member to impel such inserted coin along the chute, and insertion of a larger coin will impart the same pivotal movement to said member and an additional translational movement permitted by the length of said slot to tension said spring an additional amount proportional to the difference between the diameters of said smaller and larger coins.
